Attorney

UNITED STATES PATENT OFFICE.

JERRY W. ST. CLAIR, OF JOHNSTOWN, PENNSYLVANIA.

RAILWAY-TIE.

1,144,441.

Specification of Letters Patent. Patented June 29, 1915.

Application filed April 5, 1915. Serial No. 19,246.

To all whom it may concern:

Be it known that I, JERRY W. ST. CLAIR, a citizen of the United States, residing at Johnstown, in the county of Cambria and State of Pennsylvania, have invented certain new and useful Improvements in Railway-Ties, of which the following is a specification, reference being had to the accompanying drawings.

10 This invention relates to certain improvements in railway ties; and it is an object of the invention to provide a novel and improved device of this general character wherein the major portion is formed of metal and of such a character as to be readily rolled or pressed into shape and reducing to a minimum the necessity of machine work whereby the same may be produced with a minimum of cost.

20 Furthermore, it is an object of my invention to provide a device of this general character including a metallic casing having coacting therewith wooden cushion blocks capable of convenient application to or removal from the casing and which are also capable of being moved longitudinally thereof.

It is also an object of my invention to provide a device of this general character 30 including a metallic casing or channel section having a concaved bottom and sloping sides whereby the device will possess a maximum of strength and effectively maintain its position in ballast.

35 The invention consists in the details of construction and in the combination and arrangement of the several parts of my improved railway tie whereby certain important advantages are attained and the device 40 is rendered simpler, less expensive and otherwise more convenient and advantageous for use, all as will be hereinafter more fully set forth.

The novel features of the invention will 45 be carefully defined in the appended claim.

In order that my invention may be the better understood, I will now proceed to describe the same with reference to the accompanying drawings, wherein—

50 Figure 1 is a view in top plan of a railway tie constructed in accordance with an embodiment of my invention, a rail being shown applied thereto; Fig. 2 is a view, partly in longitudinal section and partly in side elevation, of the tie as herein embodied; Fig. 3 is a sectional view taken substantially

on the line 3—3 of Fig. 1; Fig. 4 is a sectional view taken substantially on the line 4—4 of Fig. 1; and Fig. 5 is a view, detached, in perspective of a block herein embodied.

As disclosed in the accompanying drawings, C denotes an elongated channel section or casing having its top and ends open and having its base 1 concaved in cross section throughout its entire length and its side walls 2 disposed in upwardly converging planes with their upper free longitudinal marginal portions provided with the inwardly disposed flanges 3, for a purpose to be hereinafter more particularly referred to. It will be readily perceived that the construction of the section or casing C is such as to permit the same to be readily rolled or pressed from metal, and it is to be particularly stated that the outer surfaces of the bottom 1 and sides 2 are rough-rolled in order to facilitate adhesion of ballast. At predetermined points adjacent the extremities thereof the casing or section C has its side walls 2 and flanges 3 cut out as indicated at 4, and such cut out portions are intersected by the cushion blocks 5 insertable within the section or casing C through the ends thereof and fitting snugly therein; and it is to be observed that the cut out portions 4 are of such a depth as to terminate below the upper surfaces of the blocks whereby the requisite spring or yield is afforded to the rail R resting on said blocks.

In order to protect the upper surfaces of the blocks against the action of the rails R, I find it of advantage to employ in connection with said blocks the wear plates 6 of a length in excess of the length of the cut out portions and having their ends provided with the extensions 7 projecting within and filling the cut out portions of the flanges 3. Each of the plates is provided with the openings 8 through which the retaining spikes for the rail R are adapted to pass, said spikes S penetrating the blocks 5 and serving in connection with the plates 6 to hold the blocks 5 against independent movement longitudinally of the channel section or casing 1. If desired, however, the wear plates 6 may be omitted. In which instance, the bases of the rails will coat with the cut out portions of the casing or section C to maintain the blocks 5 against longitudinal movement.

As is believed to be self-evident, the par-

ticular formation of the bottom 1 and sides 2 of the section or casing C affords a maximum of strength and assures the casing or section maintaining its position within the ballast, while the flanges 3 also serve to increase the strength of the section or casing and prevent the blocks 5 from pulling up. The flanges 3 also serve to retain within the casing or section the ballast filler F which may be cinder, dirt, concrete or any other material which may be employed with facility. In addition, the flanges 3 afford a better surface for employees walking on the track-way.

15 By having the top of the section or casing C open, it will be readily perceived that guard rails or braces may be positioned at any point desired, as is thought to be clearly apparent to those skilled in the art to which my invention appertains. It will also be readily perceived that should it be required to employ new blocks 5, the blocks in applied position may be readily forced inwardly toward the center of the section or casing C and serve as a medium for imparting additional strength to the structure. It is also possible in my present invention, should the upper surface of the blocks 5 become unduly worn, to insert between the plates 6 and said blocks supplemental wedge blocks, as is thought to be self-evident. I also find it in practice of advantage to creosote the blocks 5 and to coat the section or casing C with a preserving paint and to provide through the base or bottom 1 of the section or casing in its longitudinal margins and at points intermediate the cut out portions 4 the drainage openings 9.

From the foregoing description, it is thought to be obvious that a railway tie constructed in accordance with my invention is

of an extremely simple and comparatively inexpensive nature and is particularly well adapted for use by reason of the convenience and facility with which it may be assembled, 45 and it will also be obvious that my invention is susceptible of some change and modification without material departure from the principles and spirit thereof and for this reason I do not wish to be understood as 50 limiting myself to the precise arrangement and formation of the several parts herein shown in carrying out my invention in practice.

55 I claim:

A device of the character described including an elongated casing having its ends and top open, the bottom of said casing being concaved in cross section and the sides thereof being disposed in converging planes, 60 the upper longitudinal marginal portions of the sides being provided with inwardly disposed flanges, said sides and flanges at predetermined points adjacent the extremities of the casing being cut out, bearing 65 blocks insertible within the casing through the ends thereof and bridging the cut out portions of the casing, said cut out portions terminating below the upper surfaces of the blocks, and a wear plate resting on the 70 upper surface of each of the blocks, said plate being provided with extensions extending within the cut out portions of the casing to hold said plate against movement longitudinally of the casing. 75

In testimony whereof I hereunto affix my signature in the presence of two witnesses.

JERRY W. ST. CLAIR.

Witnesses:

M. Cwyer,
Jacob Ellenberger.
